UNITED STATES PATENT OFFICE.

ARTHUR H. SMITH, OF WORCESTER, MASSACHUSETTS, ASSIGNOR TO DOMESTIC VACUUM CLEANER COMPANY, OF WORCESTER, MASSACHUSETTS, A CORPORATION OF MASSACHUSETTS.

CLEANING DEVICE.

1,258,822.

Specification of Letters Patent.

Patented Mar. 12, 1918.

Application filed September 3, 1913. Serial No. 787,994.

To all whom it may concern:

Be it known that I, ARTHUR H. SMITH, a citizen of the United States, residing at Worcester, in the county of Worcester and 5 State of Massachusetts, have invented a new and useful Cleaning Device, of which the following is a specification.

The present invention relates to apparatus for removing dust from carpets and for 10 other like purposes, the object being to provide an improved form of combination vacuum cleaner or dust extractor and brush sweeper in a single machine in a simple, cheap and practical manner.

15 Hitherto it has been proposed to combine with a carpet sweeper of the well known type a vacuum or suction device attached to the handle of the machine and operated by hand, or to place a rotary brush in the nozzle 20 opening of the vacuum cleaning device, and it has also been proposed to combine with a dust suction device a brush operated frictionally from the floor wheels of the machine and it is to this type of machine that the 25 present invention relates.

According to the present invention I combine a rotary brush with a vacuum cleaning machine in such manner that the former can be readily removed or rendered inoperative 30 without in any way affecting the use or operation of the vacuum machine.

One embodiment of my invention will now be described in detail in connection with the accompanying drawing Figure 1 of which 35 represents a vacuum cleaner of known construction provided with a brush sweeper on its under side, according to this invention and Fig. 2 of which is a fragmentary bottom plan.

40 The apparatus comprises a casing A having a dust box B and bellows compartment C, the bellows c being mounted in this construction on the top of the box B, with the interior of which they communicate through 45 valve openings b.

In front the casing is provided with a removable nozzle D, the upper opening of 50 which communicates with a bag b' in the dust box B. The casing is shown as supported at the front on an adjustable central roller E, and at the rear on two floor wheels F which operate the bellows c by means of crank shaft f and rods f' connected to rods c' secured to the bellows. As the wheels 55 revolve, when the apparatus is pushed along

the floor by means of a handle G, the bellows will be operated to produce a partial vacuum in the box B and draw in air and dust through the nozzle D in a well known manner.

60 Behind the nozzle D I provide a sweeper brush H to gather up any dust which may have escaped being drawn in by the nozzle D. This brush is mounted in a casing H', the bottom part of which is constituted by two floors or trays one on either side of the brush H which projects downward slightly beyond them, like an ordinary carpet sweeper, the floors being preferably hinged so as to facilitate emptying of the dust. This 70 casing has flanges h' adapted to slide in corresponding guides h² secured to the under side of the box B, if desired, but I prefer to make it stationary.

The ends of the axle upon which the brush 75 is mounted or formed are provided with wheels h³ adapted to roll on the ground and so operate the brush.

The brush axle H² projects through suitable 80 openings in the side walls of the casing H' and has mounted upon its ends driving wheels h³ so that these wheels lie in the same, or approximately the same, longitudinal vertical plane as the wheels F. The shaft H², or an extension thereof, projects beyond the 85 wheels h³ and is carried in brackets J, pivoted to the sides of the casing at J' in a horizontal plane below that in which the axle H² is situated. Thus, if the brackets J are rocked about their pivots J' the wheels 90 will be raised out of contact with the floor with which they are normally in driving contact.

To facilitate this movement of the wheels 95 h³ I secure to the brackets J at the points j a lever K or handle extending across the back of the machine, so that by slightly depressing or raising the lever K the wheels h³ will be moved into or out of contact with the floor. A bent spring catch L is arranged 100 on the side of the casing H' to retain the lever K in one or other of its adjusted positions.

In operation, the machine is passed over 105 the carpet or other surface to be cleaned, and the dust is drawn through the nozzle H into the bag b' by the bellows c operated from the floor wheels F, while any dust which escapes the nozzle D is swept up by the brush H and deposited in the trays M M'. 110

If, for any reason, it is not desired to use the brush in conjunction with the vacuum device, it can be instantly thrown out of action, by pressing the lever K down by hand or foot.

While I have described my invention particularly with reference to one form of vacuum cleaner, it is to be understood that the invention is not limited to the combination or adaptation of a rotary sweeper to machines of that type.

Although I have illustrated and described a specific form of the invention, I am aware of the fact that modifications can be made therein by any person skilled in the art without departing from the scope of the invention as expressed in the claims. Therefore I do not wish to be limited to all the details of construction herein shown and described, but what I do claim is,—

1. The combination with a horizontal main casing, a support, and rollers for supporting the ends of the casing, of a brush sweeper comprising a low horizontal auxiliary casing located under and attached to the bottom of the main casing, a rotary brush carried by said auxiliary casing, rollers for operating the brush, and means for adjusting said rollers into and out of contact with the surface on which the first named rollers and support are supported.

2. The combination with a complete pneumatic cleaner comprising a main casing, a support, and rollers for supporting the end of the casing, of an independently operable brush sweeper located under the bottom of the main casing, and comprising a low flat horizontal casing, a rotary brush, dust pans adjacent to the brush, rollers, independent of the first named rollers, for operating the brush, and means for adjusting the brush and brush operating rollers up and down to render them operative or inoperative without affecting the operativeness of the pneumatic cleaner.

3. In a cleaner, the combination with a main casing, rollers for supporting one end of the casing, and a nozzle at the other end of the casing, of an auxiliary casing located under the main casing between said rollers and nozzle, a transverse rotary brush carried by the auxiliary casing, rollers located under the main casing, near the first named rollers and adapted to engage the surface to be cleaned for rotating the brush, means

for adjusting said brush operating rollers and brush into and out of operative position, and means for holding them in their adjusted positions.

4. The combination with a carpet cleaner comprising a main casing, and rollers for supporting one end of the main casing, of an auxiliary casing located under said main casing near said rollers, a brush carried by said auxiliary casing, a pair of rollers for operating the brush, and means for positively adjusting said rollers into two positions, in one of which they are in contact with the surface to be cleaned, and in the other of which they are out of contact therewith.

5. The combination with a main casing, and rollers for supporting one end of the main casing, of an auxiliary casing located under said main casing near said rollers, a brush carried by said auxiliary casing, a pair of rollers journaled on said auxiliary casing and adapted to engage the surface to be cleaned for the purpose of operating the brush, a pivoted frame on which said brush and rollers are journaled, and means for adjusting said frame about its pivot into two positions, in one of which the brush and rollers are in contact with the surface to be cleaned and in the other of which they are raised from it.

6. A cleaner having a nozzle at one end and wheels at the other, a horizontal casing between them, and an auxiliary cleaner connected to and supported by the bottom of said casing between the wheels and nozzle and having a cleaning element adapted to be lowered and raised to render it operative and inoperative independently of the elevation of the nozzle and held in either position.

7. A cleaning device having a horizontal main casing supported at its front and rear ends, and provided with a casing on the bottom thereof between the points at which the main casing is supported, said second casing having a vertically adjustable cleaning element carried thereby.

In testimony whereof I have hereunto set my hand, in the presence of two subscribing witnesses.

ARTHUR H. SMITH.
